SIGNAL TRANSLATING APPARATUS

Harry F. Olson, Princeton, N. J., a signor to
Radio Corporation of America, a corporation of
Delaware

Application March 27, 1943, Serial No. 430,788

1 Claim. (Cl. 177—386)

1

This invention relates to signal translating apparatus, and more particularly to a loud speaker which is especially useful in submarine signalling.

Various forms of sub-aqueous loud speakers have been provided heretofore for submarine signalling. For successful operation of a loud speaker submerged in water, it is essential not only that the pressure on both sides of the diaphragm be the same, but it is highly desirable that the stiffness thereof be maintained constant, that is, that the stiffness of the diaphragm be the same under water as it is in air. So far as I am aware, submarine loud speakers of the prior art have failed in this respect.

The primary object of my present invention is to provide an improved sub-aqueous loud speaker wherein the diaphragm will always have the same pressure on each side thereof regardless of the depth to which the loud speaker is submerged in water or other fluid medium.

More particularly, it is an object of my present invention to provide a pressure compensator for sub-aqueous loud speakers by means of which the same fluid pressure will be maintained on both sides of the loud speaker diaphragm, while at the same time presenting a low impedance to the inside surface of the diaphragm and a high impedance to the outside surface of the diaphragm.

Another object of my present invention is to provide an improved sub-aqueous loud speaker which will transmit acoustical vibrations with great efficiency.

Still another object of my present invention is to provide an improved sub-aqueous loud speaker the characteristics of which are independent of the depth to which the loud speaker may be immersed in water.

A further object of my present invention is to provide an improved sub-aqueous loud speaker as aforesaid in which the stiffness of the vibrating system is maintained at a relatively low value.

It is also an object of my present invention to provide an improved sub-aqueous loud speaker as set forth above which is simple in construction, inexpensive in cost, and highly efficient in use.

In accordance with my present invention, I provide a collapsible enclosure which I couple to the back side of the loud speaker diaphragm through a passageway which offers a high impedance to the passage of fluid at acoustic frequencies. Around the collapsible enclosure, I provide a rigid enclosure having an opening therein which also affords a high impedance to the passage of fluid therethrough at acoustic fre-

2

quencies. When the loud speaker is immersed in water or other fluid medium, the medium enters the opening in the rigid casing and causes the aforementioned enclosure to collapse partially, thus forcing the air or other fluid entrapped therein through the previously mentioned passageway into another fluid-tight chamber which is closed off by the diaphragm. At the same time, since the diaphragm is exposed to the medium on its front surface, the medium also acts directly on the diaphragm. Since the collapsed enclosure forces the entrapped fluid therein into the chamber which backs up the back side of the diaphragm, the same, steady pressure is created on both sides of the diaphragm. At the same time, the collapsible enclosure or equalizer presents a high alternating impedance to the medium because of the fact that the rigid enclosure surrounds it, and it is coupled to the medium exterior of the rigid casing only through the small aperture or opening in the casing.

The novel features that I consider characteristic of my invention are set forth with particularity in the appended claim. The invention itself, however, both as to its organization and method of operation, as well as additional objects and advantages thereof, will best be understood from the following description of one embodiment thereof, when read in connection with the accompanying drawing in which the single figure is a central, sectional view of one embodiment of this invention.

Referring more particularly to the drawing, there is shown a loud speaker comprising a cylindrical magnet 1, a back plate 3, a yoke plate 5 and a center pole piece 7 all connected together in fluid-tight relation. The yoke plate 5 is provided with a central opening of larger diameter than that of the pole piece 7 whereby to form an air gap 9 in well known manner. Connected to the yoke plate 5 in fluid-tight relation thereto is a vibratory diaphragm 11 provided with a voice coil 13 located in the air gap 9. The magnet 1, the back plate 3, and the yoke plate 5 may be coated on the exposed surfaces with a corrosion resistant coating 15, the diaphragm 11 being also made of a corrosion resistant material. The structure thus far described provides a fluid-tight chamber 17 within the field structure constituted by the magnet 1 and the plates 3 and 5, the air gap 9 affording communication between the chamber 17 and the exterior of the field structure, and the diaphragm 11 closing off the chamber 17 from the exterior of the loud speaker. The back plate 3 is provided with an opening 19

and with a concentrically arranged flange 21 over which is fitted a collapsible enclosure 23 of yieldable material, such as relatively soft rubber. The member 23 is relatively less stiff than the diaphragm 11 and encloses a second chamber 25 which is in communication with the chamber 17 only through the opening 19. The enclosure 23 has fluid-tight connection with the back plate 3, and for this purpose, it may be provided with an outwardly extending flange 23a which rests against the back plate 3 and which is held tightly thereagainst and against the flange 21 by a ring 27.

Surrounding the collapsible member 23 preferably, but not necessarily, concentric therewith and in spaced relation thereto, whereby to provide a third chamber 31, is a rigid casing 29 which has fluid-tight connection with the ring 27 and the flange 23a. The casing 29 has a small aperture or opening 33 therein which affords communication between the chamber 31 and the exterior of the casing. The opening 33 is of such dimensions that it affords a high impedance to the passage of a fluid between the chamber 31 and the exterior of the casing 29 at acoustic frequencies.

A loud speaker constructed as above described will normally have air entrapped within the chambers 17, 25 and 31. When such a loud speaker is immersed in another fluid medium, such as water, the water pressure against the front surface of the diaphragm 11 would tend to displace the diaphragm from its normal position. However, the water is free to enter the chamber 31 through the opening 33 and to partially collapse the member 23 (for example, to the dot and dash line position shown in the drawing). Thus, some of the air in the chamber 25 is forced into the chamber 17 through the opening 19 until the pressure on the back side of the diaphragm 11 is equal to the water pressure on the front side thereof. Accordingly, the diaphragm 11 remains in its normal position and its stiffness is not altered. Consequently, the diaphragm remains free to reproduce faithfully in the form of acoustic vibrations the electrical signal impulses supplied to the voice coil 9 through suitable means (not shown). The high impedance which the passageway 19 offers to vibrations at acoustic frequencies will prevent a transfer of entrapped air between the chambers 17 and 25 during operation of the loud speaker. Also, since the aperture 33 offers a high impedance to the passage of the water

therethrough at acoustic frequencies such as are set up therein by the diaphragm 11, the collapsed member 23 will remain in the dot and dash line, collapsed condition.

From the foregoing description, it will be apparent to those skilled in the art that I have provided an improved loud speaker having all the advantages heretofore enumerated. Although I have shown and described but one embodiment of my invention, it will, no doubt, be apparent to those skilled in the art that many other modifications thereof are possible. I therefore desire that my invention shall not be limited except insofar as is made necessary by the prior art and by the spirit of the appended claim.

I claim as my invention:

In signal translating apparatus, the combination of a magnetic field structure forming a first chamber and including an air gap affording communication between said first chamber and the exterior of said field structure, a vibratory member including a voice coil disposed in said air gap, said member having fluid-tight connection with said structure and closing said air gap off from the exterior of said apparatus, said field structure including an opening in one wall thereof communicating with said first chamber, a collapsible member having fluid-tight connection with said wall and forming a second chamber in communication with said opening, and a rigid casing surrounding said collapsible member in spaced relation thereto providing a third chamber around said member, said casing having an opening therein affording communication between said third chamber and the exterior of said apparatus.
